UNITED STATES PATENT OFFICE.

ADRIAN O. VAN DERVORT, OF TROY, NEW YORK.

PACKING.

SPECIFICATION forming part of Letters Patent No. 759,330, dated May 10, 1904.

Application filed October 24, 1903. Serial No. 178,304. (No model.)

To all whom it may concern:

Be it known that I, ADRIAN O. VAN DERVORT, a citizen of the United States, residing in Troy, in the county of Rensselaer and State 5 of New York, have invented certain new and useful Improvements in Packings, of which the following is a specification.

This invention relates to and has for an object to provide an improved packing and 10 means for controlling the same, permitting it to conform to irregularities in the position of the rod or shaft which is packed.

In the drawings accompanying and forming part of this specification a form of my invention 15 is illustrated, wherein—

Figure 1 shows a piston or other rod in elevation and partly broken away and surrounding the same an embodiment of my invention shown in central cross-section. Fig. 2 is an 20 end view thereof. Fig. 3 is a perspective showing the parts disassembled. Fig. 4 is a view similar to Fig. 1, but showing the position assumed by the packing when the rod is shifted laterally from its normal position. 25 Fig. 5 is a perspective illustrating a form of metallic packing-ring which may advantageously be employed in this device, and Fig. 6 is a diagrammatic view showing a piston-cylinder and cross-head and a crank with the 30 connected parts and will be referred to in the description of the invention.

It is well known that a piston-rod will at times from various causes move a little to one side or the other either by wearing of parts 35 or the settling of certain of the surroundings of the structure, and if the packing is rigidly held such movement will strain the packing or cause it to fail to meet the object of its employment. It is found that such movement 40 of the shaft may not only be so that its outlines move to a position parallel to the normal position, but it also vibrates, or the shaft might be regarded as rotating upon a point in the line of its axis. This invention is intended 45 to efficiently pack a rod which is liable to such action, and in the drawings herein a shaft is shown (designated in a general way by 10) having in the present instance an enlargement 11 and a reduced tapering portion 12, which in practice will take into the

cross-head if the employment of the rod is one wherein a cross-head is called into requisition. The rod passes freely through a housing (designated in a general way by 13) which may be integral with the end of the 55 cylinder and comprise what is frequently called a "stuffing-box." The stuffing-box is shown as closed by a cap-piece 14, in the present instance bolted to the stuffing-box by means of tap-bolts 15. Some suitable form 60 of packing may be employed. In the present instance a series of metallic rings 16 is illustrated, each of which rings in the present instance comprises segmental portions 17, having lapped or sliding joints 18. Flanges 19 65 are shown upon the segments, and a sustaining-ring 20, lying between the flanges, to hold the segments together and against the rod. A number of these rings are shown as contained within a casing 21, which casing has end 70 portions 22 in the form of rings, each of which receives an end of the casing 20 in a rabbet. The end rings 22 each has an outer face 23, and such rings carry within them packing-segments 24, which will afford a bearing for 75 the rod which is packed and to which the device is applied, so that when the parts are assembled and in position upon the rod any lateral movement or "wabbling" of the rod will cause the entire casing and set of rings to 80 move with it, they being of course prevented from longitudinal movement with the rod by the surrounding parts. As herein illustrated, the casing is provided with steam-ports 25, whereby steam may find access into a chamber 85 which is left between the inside of such casing and the outside of the packing, so that the steam will cause such packing to closely adhere to the shaft and efficiently pack the same.

The inner face of the cap 14 is provided with 90 a cup-shaped bearing 26, having a concave formation against which a bearing-ring 27 may be placed, which bearing-ring is shown as having a corresponding convex face 28 to engage therewith, and the inner space of the 95 ring is shown as of larger diameter than the diameter of the rod packed. This ring is also provided with a plane face 29 to engage one of the end faces 23 and permit the same to slide thereon. A similar ring is provided for the 100

other end of the packing-casing and fits into a concave cup 30 upon a follower 31, conforming to the chamber within the stuffing-box, a suitable spiral spring 32 being shown for 5 the purpose of placing the follower and the parts in close engagement.

It will be seen that the inside diameters of the follower, the rings, the entrance to the stuffing-box, and the cap are of larger diameter than the diameter of the shaft, but that the bearings 24 closely conform to the shaft, whereby any movement of the shaft will be imparted to the rings—that is, for instance, referring to Fig. 4, if the shaft moves from the 15 dotted-line position (indicated by 33) to the full-line position the packing-casing and the rings 22 will move with the shaft. Such movement is shown as parallel to the axis of the shaft; but in case the shaft moves at an angle 20 to its axis then the packing-casing will move as a whole with the shaft, the faces 23 always being substantially transverse or at about right angles to the axial line of the shaft, and the faces 28 of the rings 27 will also be forced 25 to move in such transverse plane, their rounding convex faces rolling in the cup-faces in which they are placed somewhat after the analogy of a ball joint or bearing, whereby the packing will always be held firmly incident to the movement of the follower, but 30 will be permitted to conform to any erratic movements of the rod. The follower is provided with steam-ports 34 to supply steam for the packing-casing.

35 By referring to Fig. 6, wherein is shown a cylinder 35, having mounted therein a piston 36, connected by a piston-rod 37 to a cross-head 38, shiftable upon cross-head slides 39 and pivoted to a pitman 40, embracing a crank-pin 41, and assuming that steam is supplied to the cylinder in the direction of the arrow and the pitman is moving in the direction of the arrow upon it, then the pull of the cross-head will be in the direction of the arrow 42, 45 which in course of time will wear the bearings for the cross-head, as will also the gravity of the parts upon such bearing, so that it will be necessary to maintain the packing in an efficient condition that it adjust itself to this 50 condition of wear. It may also be possible that when the parts assume the position illustrated in Fig. 6 and move as therein indicated the piston-rod will "wabble" toward one side and that upon their return stroke will wabble 55 in the opposite direction, this of course being exaggerated in some instances when the parts are given freedom in their bearings or owing to some other causes maintained in connection with the parts that are set up, so that it will 60 be seen that no matter what position the shaft assumes the packing should be maintained upon the rod with its full virtue.

The cap 14 may carry a cap 43, secured thereto by some convenient means, here 65 shown as tap-bolts 44, and having within it a

pair of rings 45, each comprised of separable segments, these rings being a sufficient distance from the shaft to clear it in its movements and having between them some suitable lubricant-retaining material 46, which may 70 be supplied with lubricant through an oil-hole 47, whereby the shaft will receive sufficient lubrication to maintain it in proper working order in connection with the packing—that is, assuming, of course, that the 75 piston-rod is in a position which requires lubricant; otherwise it may be omitted. Cap 14, as shown, is packed by a ring 50.

In locomotive-engines, particularly the high-speed engines, there is considerable resiliency of the parts, causing the piston-rod to have considerable vibration or lateral movement, which when ordinary forms of packing are used distorts and wears the packing and permits the same to leak. When the 80 steam does leak from such packing, it will usually pursue a course to come in front of the cab-windows, not only covering them with condensation and making them opaque, but also producing a dense cloud in front of 85 the engineer's vision, making it impossible for him to see signals or the track in front of him and frequently requires the reduction of speed. This one instance of the result of the present form of deficient packing illustrates 90 the dangers and inconveniences to which the public is subjected. The present improvement, however, applied in similar surroundings will efficiently pack the piston and prevent such dangerous and annoying escape of 95 steam.

This device comprises what may be called a "self-contained packing"—that is, the packing may be properly assembled in the casing and the whole held together either by some 105 part of the device or by means of a convenient clamp and will then be in suitable condition to be held in readiness for use when it may be desired to repack a piston-rod or other shaft where it will be employed. The packing being 110 self-contained may be assembled ready for application to a piston-rod, provided the end of the rod over which the same is to be passed is not of greater diameter than the bearing position thereof, so that no adjustment is required and the packing is always in condition 115 for use when demanded. Such parts may be removed bodily from the rod when for any reason it is desired to do so and a new packing or the original replaced bodily and in an 120 assembled form.

In Fig. 1 the ring 27 is shown bored out to form a space 55 large enough to permit said ring to pass over the enlarged end 11 of the piston-rod, and similarly the outer cap 43 is 125 shown bored with its central part large enough to permit its passage over said piston-rod shoulder 11, and for holding the packing 46 in place within the said cap plates 45 are provided, these being made in halves, so that when 130

the said cap 43 is slipped off over the end of the piston-rod these divided plates 45 may be taken off of the rod by separating them radially. After this the member 14 may be unfastened and removed, it also having a sufficiently large central aperture for permitting this member to pass over said piston-rod shoulder 11. Following this the aforesaid adjustable member 27 is similarly free to pass over the piston-rod end, after which it is then possible to remove the next succeeding member of the packing device—that is, the ring 22, which engages and holds in place the divided ring 24. By slipping the member comprising the parts 22 and 24 along toward the enlarged end of the piston-rod the said divided ring 24 may be pushed out of the ring 22 and the divided ring then separated and taken off from the piston-rod, whereupon the ring 22, by reason of its enlarged central opening, (for receiving said divided ring 24,) will also be free to pass off the piston-rod over its enlarged end portion. In similar manner all of the members of the packing device may be readily removed one after the other, and when a new packing device is to be put in place or a disassembled packing device is to be reassembled upon the rod this operation may be performed by reversing the manipulation of the parts, the assembled packing mechanism being then slipped into its receiving-chamber, the outer cap put in place, and the whole apparatus thus made ready for use.

This device by reason of its adaptation for removal and renewal of the various portions is especially adapted for application to piston-rods which have been re-turned, in which case it is usual to leave the extreme end portion of its original full size, in which class of cases it would of course be necessary to remove by separation, as in the case of the split ring 24, any rings which might be made of a size for properly fitting such a reduced piston-rod. In regard to the half-rings 24 where the packing is to be used for rods not having an enlarged end the ring 22 may be made to come close to the rod, and so take the place of the divided ring 24.

It will be readily apparent that the center from which the faces of the cups and the bearing-rings are struck will be such that the proper rolling or ball-bearing movement will be effective with the least amount of resistance or wear.

It will be seen that the various parts are capable of working as herein described and that the packing will be held against the rod and will not be permitted to receive any strains or distortions which will wear it out or weaken it or prevent it from acting efficiently.

Although metallic packing is herein illustrated, yet it will be apparent that other packing may be resorted to if found desirable in practice.

Having described my invention, I claim—

1. In a packing the combination of a housing, a cup having a concave face rigid therewith; a follower in the housing carrying a cup having a concave face; a number of packing-rings; a casing to carry the same, having plane faces on its ends; a pair of rings having plane faces to abut and slide upon the end faces of the casing and convex faces to occupy and turn in the cups. 70

2. In combination with a rod, of means to carry packing therefor and comprising a casing having a packing-chamber, and a bearing at each end for the rod packed and organized to constrain the casing to maintain a position constant relative to the perimeter of the rod, 80 a plurality of packing-rings in said chamber independently movable in a radial plane, and means to admit steam to the chamber to compress the packing-rings. 75

3. The combination with a rod, of a stuffing-box; a plurality of packing-rings therein and upon the rod; a casing to hold the rings and having a bearing at each end for the rod and a face upon each side of the casing transverse to the line of the axis of the rod; a cup-shaped bearing within the stuffing-box; a follower also within the stuffing-box and having a cup-shaped bearing; and a pair of rings each having a plane face to mate with the plane faces of the case and faces to mate with 95 the cup-shaped bearings. 90

4. In combination with a stuffing-box and a rod, of a series of packing devices; means to constrain the packing devices to move in unison with the erratic movements of the rod; a ball-joint between each end of the same and the stuffing-box; and means to permit transverse movement of said holding means relative to said ball-joints. 100

5. A packing device comprising a body of packing; means to constrain the packing to move in unison with the erratic movements of the rod packed; a ball-joint at each end of the same; and bearings to permit transverse movement of said holding means relative to 110 said ball-joints. 105

6. The combination with a rod, of a stuffing-box; a plurality of packing-rings therein and upon the rod; a casing to hold the rings and having bearings for the perimeter of the rod; faces upon the casing transverse to the line of the axis of the rod; a pair of cup-shaped bearings within the stuffing-box; a pair of rings each having a plane face to mate with the plane faces of the case and faces to mate with the 120 cup-bearings; and steam-ports to supply steam to the casing to act on the packing. 115

7. The combination with a rod, of a stuffing-box; a packing therein and upon the rod; a casing within the stuffing-box to hold the packing and having bearings for the perimeter of the rod; faces upon the casing transverse to the line of the axis of the rod; a cup-shaped bearing within the stuffing-box; a follower; a similar bearing on the follower; a pair of 125 130

rings each having a plane face to mate with the plane faces of the casing and faces to mate with the cup-bearings; a chamber in the casing outside the packing; a steam-port in the 5 casing; and a steam-port in the follower to supply steam thereto.

8. The combination with a rod; of a stuffing-box; a plurality of divided packing - rings therein and upon the rod; a casing to hold the 10 rings and having a divided bushing at each end constituting bearings for the perimeter of

the rod; faces upon the casing transverse to the line of the axis of the rod; a pair of cup-shaped bearings within the stuffing-box; a pair of rings each having a plane face to mate with the plane faces of the case and faces to mate with the cup-bearings. 15
